UNITED STATES PATENT OFFICE.

ADAM EMIL KELLER, OF NEW YORK, N. Y., ASSIGNOR TO THE KELLER MANUFACTURING COMPANY, OF NEW YORK, N. Y., A CORPORATION OF NEW YORK.

DESIGN FOR A BROOCH, BADGE, OR SCARF-PIN.

44,064.

Specification for Design.

Patented May 20, 1913.

Application filed March 6, 1913. Serial No. 752,493. Term of patent 7 years.

To all whom it may concern:

Be it known that I, ADAM EMIL KELLER, a citizen of the United States of America, residing in New York, in the borough of Manhattan, county and State of New York, have invented a new, original, and ornamental Design for Brooches, Badges, or Scarf-Pins, of which the following is a specification, reference being had to the accompanying drawing, forming part thereof.

The figure shows a front-elevation of a brooch, badge or scarf-pin, showing my new design.

I claim:

The ornamental design for a brooch, badge or scarf-pin, as shown.

ADAM EMIL KELLER.

Witnesses:

PAUL GOEPEL,
JOHN MURTAGH.
